UNITED STATES PATENT OFFICE.

HENRY P. CLAUSEN, OF MOUNT VERNON, AND CHARLES L. GOODRUM, OF NEW YORK,
N. Y., ASSIGNEES TO WESTERN ELECTRIC COMPANY, INCORPORATED, OF NEW
YORK, N. Y., A CORPORATION OF NEW YORK.

TELEPHONE SYSTEM.

1,374,188.

Specification of Letters Patent.

Patented Apr. 12, 1921.

Application filed May 11, 1918. Serial No. 233,970.

To all whom it may concern:

Be it known that we, HENRY P. CLAUSEN and CHARLES L. GOODRUM, citizens of the United States, residing at Mount Vernon, in 5 the county of Westchester, State of New York, and at New York, in the county of New York, State of New York, respectively, have invented certain new and useful Improvements in Telephone Systems, of which 10 the following is a full, clear, concise, and exact description.

This invention relates to telephone systems and more particularly to those in which inter-office or inter-city trunk line circuits 15 are employed.

In such systems, it is a common practice to build up or complete a sectionalized trunk line for telephonic communication between two widely separated switching centers or 20 stations by joining together through suitable connecting means at various intermediate switching centers or stations, the normally independent trunk circuits interconnecting such intermediate stations.

25 It is the object of the present invention to provide an improved signaling arrangement for use in connection with such systems whereby the building up of such sectionalized trunks will be greatly expedited, due to 30 the fact that the operators at the various stations may readily determine the status of the various interconnecting trunk circuits.

To attain this object in accordance with a feature of this invention, means is provided 35 at each switching center or station, which is operative when all trunks between that and some other station are contemporaneously engaged, to automatically convey such information to operators at other stations, 40 thus eliminating the necessity of the originating operators ascertaining from each of the affected operators whether the desired trunk lines are engaged.

The nature of the invention will be more 45 clearly understood from the following specification and the annexed drawing in which the figure shows diagrammatically several trunk lines normally joining the intermediate stations, and a typical connecting or link 50 circuit for interconnecting such trunks at the stations.

In the drawing, the switching center or station A is joined with station B by means of trunk circuits F and I. The station B is 55 joined with station C by trunk circuit G and

with station D by trunk circuit J, while station C is joined with station D by trunk circuit H. In each case, it is understood that although only a few trunk lines are shown, a plurality of each class of such trunk 60 lines may join the respective stations. Several link or connecting circuits E of any suitable type may also be furnished at each station for interconnecting the trunk circuits terminating thereat. Each trunk terminal is 65 provided with a jack and a sleeve relay, such as jack 7 and relay 8 of the trunk circuit F, for coöperation with the plugs 1 and 4 of the cord circuit E. At each station, various signaling devices, such as 10, are controlled by 70 associated relays, such as 9, to indicate to the operator at such station the status of portions of the sectionalized trunk line interconnecting other stations.

It is believed that the invention will be 75 more fully comprehended from the following description of the operation thereof.

Assuming that at station A, the plug 4 of the cord circuit E is inserted in jack 7 of trunk circuit F, the relay 8 operates and the 80 lamp 5 lights over a circuit established from battery through lamp 6, resistance 5, sleeve contacts of plug 4 and jack 7, and winding of relay 8 to ground. If the plug 4 of another cord circuit E at station A is contemporaneously connected with jack 25 of trunk circuit I, relay 26 is operated in a similar manner, whereupon, due to the serial relation of the contacts of relays 8 and 26, relay 31 is operated over a circuit established from 85 battery through the winding of relay 31, ring conductors of trunk circuits J and I, and contacts of relays 26 and 8 to ground. Lamp 32 is thereupon lighted over a circuit from battery through the contact of relay 90 31 and lamp 32 to ground, to notify the operator at station C that trunk circuits F and I are engaged. Relay 33 is also operated over a circuit extending from battery 95 through the winding of relay 33 to the ring conductor of trunk circuit J where it joins the operating circuit of relay 31. By the consequent lighting of lamp 34 over a circuit from battery through the contact of relay 33 and lamp 34 to ground, the operator 100 at station D also is notified that the trunk circuits F and I are engaged.

It is evident that other trunk circuits similar to trunk circuits F and I connecting stations A and B may be added and by the interconnecting of 105 110

the contacts of the sleeve relays in series relation with the corresponding contacts of relays 8 and 26, the engagement of all such trunk circuits would cause the lighting of 5 lamps 32 and 34 in a similar manner.

Similarly upon the insertion of plug 1 of cord circuit E located at station B in jack 11 of trunk circuit F, relay 12 operates and lamp 3 lights over a circuit from battery 10 through lamp 3, resistance 2, sleeve contacts of plug 1 and jack 11 and winding of relay 12 to ground. When another similar link circuit E is also connected with the trunk circuit I, by the insertion of plug 1 in jack 15 27, relay 28 operates over a circuit similar to the operating circuit of relay 12, and due to the serial connection of the contacts of relays 12 and 28, ground is thereby connected to the ring conductors of trunks I and J to 20 cause the operation of relays 31 and 33 and the consequent lighting of lamps 32 and 34 as previously described. Thus a connection made with either terminal of all of the trunk circuits such as F and I joining stations A 25 and B causes the display of signals at stations C and D.

If cord circuits similar to E are connected with trunk circuits G and J at station B, by means of plug 4 inserted in jacks 13 and 29 30 respectively, relays 14 and 30 operate in the manner described for relays 8 and 26, and ground will be connected to the ring conductor of trunk circuit J, due to the serial relation of the left-hand contacts of relays 35 14 and 30, thereby causing the operation of relays 31 and 33 and the consequent lighting of lamps 32 and 34 as before. Relay 14, in operating, also completes a circuit from battery through the winding of relay 9, ring 40 conductor of trunk circuit F and right-hand contacts of relays 14 and 30 to ground. Relay 9 thereupon operates, causing the lighting of lamp 10 at station A over a circuit from battery through the contact of relay 9 45 and lamp 10 to ground. The lighted condition of lamp 10 serves to automatically indicate to the operator at station A that trunk circuits G and J are engaged.

In case cord circuit E is connected with 50 trunk circuit G at station C by the insertion of plug 1 in jack 17, relay 18 operates in the manner described for relay 8. By the closure of its right-hand contact, relay 18 establishes a circuit from battery through the 55 winding of relay 22, tip conductor of trunk circuit H and the right-hand contact of relay 18 to ground. Relay 22 thereupon operates, lighting the lamp 21 over a circuit from battery through the contact of relay 60 22 and lamp 21 to ground. Thus, the operator at station D is notified of the engaged condition of trunk circuit G. It is evident that other trunk circuits similar to trunk circuit G may be added and the contacts of relays similar to relay 18 wired *in seriatim* as 65

shown for relays 8 and 26. In case plug 4 of cord circuit E is also inserted in jack 13 of the trunk circuit G at station B and therefore relay 14 is operated, a circuit will also be established from battery through the winding of relay 9, the ring conductor of trunk circuit F, the right-hand contact of relay 14, the tip conductor of trunk circuit G and the left-hand contact of relay 18 to ground. Relay 9 operates, causing the lighting of 70 lamp 10 at station A to notify the operator thereof that the trunk circuit G is engaged.

If cord circuit E is connected with the trunk circuit H at the station C by the insertion of plug 4 in jack 19, relay 20 operates 75 in the same manner as previously described for relay 8. A circuit is thereupon established from battery through the winding of relay 15, ring conductor of trunk circuit G and the contact of relay 20 to ground. Relay 15, in operating, lights the lamp 16, over a circuit from battery through the contact of relay 15 and lamp 16 to ground, thereupon notifying the operator at station B that trunk circuit H is engaged. As mentioned 80 in connection with trunk circuit F, other similar trunk circuits may be added by serially interconnecting the contacts of the respective sleeve relays.

In case cord circuit E is connected with 85 trunk circuit H at station D by the insertion of plug 1 in jack 23, relay 24 operates in manner described for relay 8, and a circuit is completed from battery through the winding of relay 15, ring conductors of trunk circuits G and H and the contact of relay 24 to ground. Relay 15 thereupon operates and, as before, the consequent lighting of the 90 lamp 16 indicates to the operator at station B that trunk circuit H is engaged.

It will be evident from the above description that numerous other combinations and arrangements of the signaling means are possible, dependent upon the arrangements of the trunk circuits joining the intermediate stations and the service rendered 95 thereby.

What is claimed is:

1. In a telephone system, a plurality of stations, a plurality of trunk circuits interconnecting the stations, a plurality of link circuits at each station for interconnecting the trunk lines terminating thereat to form a sectionalized trunk line circuit joining normally disconnected stations, and means 110 to automatically indicate at the normally disconnected stations the status of the trunks normally interconnecting the other stations.

2. In a telephone system, two widely separated stations, a plurality of intermediate stations, a plurality of trunk circuits interconnecting the intermediate stations, a plurality of link circuits at each intermediate station for interconnecting the trunk cir- 115 120 125 130

- cuits terminating thereat to comprise a communicating trunk line circuit between the widely separated stations, and signaling means for indicating at the widely separated stations when all trunk circuits interconnecting any two intermediate stations are engaged, thereby preventing the completion of a trunk line circuit between the widely separated stations.
3. In a telephone system, a plurality of switching points, a group of trunk circuits extending from each switching point to another, a plurality of link circuits at each switching point to interconnect the trunk circuits thereat to form sectionalized trunk line circuits joining normally disconnected switching points, and signaling means at the normally disconnected switching points automatically responsive to the contemporaneous engagement of the link circuits with all trunk circuits comprising a group normally interconnecting other stations.
4. In a telephone system, a plurality of switching points, a group of trunk circuits extending from each switching point to another, link circuits at each switching point for connection with the trunk circuits extending therefrom, a relay associated with each trunk circuit at a switching point operating upon the connection of a link circuit with the trunk circuit, the contacts of the relays for all trunk circuits of a group being serially interconnected, and signaling means at another station responsive to the contemporaneous closure of the serially in-

terconnected contacts associated with a group of trunk circuits.

5. In a telephone system, a plurality of switching points, a group of trunk circuits extending from each switching point to another, link circuits at each switching point for interconnecting the trunk circuits extending therefrom to form a through trunk line circuit interconnecting normally disconnected switching points, a relay at each switching point associated with each trunk circuit controlled by the connection of a link circuit with the associated trunk circuit, and signaling means at a normally disconnected switching point controlled by the co-operation of relays at an intermediate switching point.

6. In a telephone system, a plurality of exchanges, a plurality of trunk circuits for establishing connections between said exchanges, and means at each exchange for indicating the condition of the trunk circuits interconnecting other exchanges.

7. In a telephone system, a series of exchanges, a plurality of trunk circuits for establishing connections from any one of said exchanges to each of the other exchanges, and means at each exchange for indicating the condition of trunk circuits interconnecting any other two exchanges of the series.

In witness whereof we hereunto subscribe our names this 8th day of May, A. D. 1918.

HENRY P. CLAUSEN.
CHARLES L. GOODRUM.
